UNITED STATES PATENT OFFICE

JOHN H. SMITH, OF MOUNT VERNON, NEW YORK, ASSIGNOR TO WESTINGHOUSE ELECTRIC & MANUFACTURING COMPANY, A CORPORATION OF PENNSYLVANIA

CONDENSER

Application filed December 9, 1929, Serial No. 412,800. Renewed November 13, 1931.

My invention relates to apparatus for condensing gaseous media and particularly to apparatus of the surface type intended primarily for condensing steam and it has for 5 an object to provide apparatus of the character designated which shall be so constructed and arranged as to effectively utilize the entire cooling surface of the apparatus in order that it may operate at a very high heat trans- 10 fer rate.

It has for a further object to provide a condenser of the surface type and of relatively large capacity which shall be provided with intermediate tube-supporting sheets so 15 arranged as to permit an unrestricted circulation of the gaseous media within the condenser shell longitudinally of the tube nest as induced by the difference in heat heads ob- 20 taining between the cooling water inlet or cold portion of the condenser and the cooling water outlet or relatively warm portion of the condenser.

It has for still another object to provide a condenser of large capacity which shall 25 be so arranged as to provide for the circulation of steam and non-condensable gaseous media longitudinally of the condenser from the warm portion of the cooling tube nest toward the cold portion thereof in order that 30 proper distribution of the steam may be obtained and maximum cooling of the non-condensable gaseous media effected.

It has for still another object to provide a condenser of the foregoing character where- 35 in the longitudinal movement of the steam and non-condensable gaseous media from the relatively warm portion of the condenser toward the relatively cold portion thereof shall assume a path or route so arranged as to 40 insure ample transfer of heat to the tube nest in order that the longitudinally moving steam may be condensed and in order that the longitudinally moving non-condensable gaseous media may be cooled.

45 It has for still another object to provide a condenser of the foregoing character which shall utilize the coldest portion of the tube nest to cool the non-condensable gaseous media prior to the removal of the same from 50 the condenser.

It has for still another object to provide a condenser of the foregoing character which shall be of the coreless type in that the tube nest shall be so arranged as to embody a longitudinally extending cavity for the circulation of gaseous media from the relatively warm portion of the tube nest toward the relatively cold portion of the tube nest. 55

It has for still another object to provide a condenser of the foregoing character which shall be of the single pass type in that the water flows through the tube nest in a single direction and of the radial flow type in that the steam enters the tube nest from the greater portion of its periphery and the air and non-condensable gaseous media are withdrawn, laterally, from an interior or central portion 60 of the tube nest. 65

These and other objects are effected by my invention, as will be apparent from the following description and claims, taken in connection with the accompanying drawings, forming a part of this application, in which: 70

Fig. 1 is a view, in longitudinal sectional elevation, of a single pass condenser arranged 75 in accordance with my invention;

Figs. 2, 3 and 4 are transverse, sectional views taken on the lines II-II, III-III and IV-IV of Fig. 1, respectively;

Fig. 5 is a view, in longitudinal sectional elevation, of a two pass condenser constructed 80 in accordance with my invention; and,

Fig. 6 is a transverse, sectional view taken on the line VI-VI of Fig. 5.

In the operation of steam condensers, it 85 has been well known for many years that the cooling water assumes progressively increasing temperatures as it travels through the tubes of the nest from the inlet to the discharge water box. In other words, the portion of the condenser adjacent to where the cooling water enters the same may be termed the cold portion while the portion adjacent to where the cooling water leaves the tube nest may be termed the warm portion. As a 90 result of these differences in temperature, different heat heads prevail within the condenser shell structure, the cold portion of the condenser having a relatively high heat head and the warm portion a relatively lower 95 100

heat head. This condition is especially pronounced in condensers of the single pass type wherein there is a tendency for the steam to flow longitudinally of the condenser shell in a direction from the outlet water box end of the condenser toward the inlet water box end.

In condensers of large capacities which are necessarily quite long, some means must be provided for supporting the tube nest intermediate of its ends and it has been the practice for many years to provide longitudinally spaced intermediate supporting sheets, which intermediate supporting sheets prevent sagging or vibration of the condenser tubes. 10 However, such intermediate tube supporting sheets may seriously interfere with the free and natural longitudinal circulation of the gases within the condenser shell from the warm end or region of relatively low heat 15 head to the cold end or region of relatively high heat head. I have, therefore, conceived of a form of condenser which may be manufactured in large capacities and in which the tubes are properly supported by the required 20 number of intermediate tube supporting sheets, but which, at the same time, is so arranged that the natural tendency for the steam to flow from the warm end to the most effective end, that is, the cold end, is fully 25 utilized to facilitate the heat absorbing process.

In accordance with my invention, I prefer to arrange the tube nest of my condenser so that it embodies a longitudinally extending 30 cavity, which cavity extends through the intermediate tube supporting sheet or sheets and which provides for the free and natural circulation of gaseous media from the warm toward the cold end of the tube nest. More 35 particularly, I prefer to employ an arrangement of the tube nest such as disclosed and claimed in my U. S. Patent No. 1,721,261 issued July 16, 1929 for Condenser and in an application of H. L. Guy, Serial No. 155,697, 40 entitled Vapor condenser, both said patent and application being assigned to the Westinghouse Electric and Manufacturing Company. In accordance with the foregoing inventions, the tube nest is arranged in the form 45 of an annular band so as to provide an internal, longitudinally-extending core space which is devoid of tubes. Such a form of tube nest is preferably, although not necessarily, employed with condensers of the 50 radiol flow type, that is, condensers wherein the nest of tubes is substantially surrounded by a steam belt and the gaseous media is drawn radially across the nest removed from an interior portion thereof.

55 By arranging the condenser in this manner, the tube nest comprises a relatively thin annular band, the exterior of this thin annular band being exposed to the entering steam and the non-condensable gaseous media being removed from the core space. As will be ap-

parent, the travel of the steam radially across the relatively thin annular band of tubes is relatively short and hence pressure drop across the condenser is minimized. The gaseous media entering the internal core space is 70 permitted to freely flow toward the inlet water box or coldest end of the condenser and, in accordance with my invention, this gaseous media is directed into contact with the cold end of that portion of the tube nest which is adjacent to the core space. In this way, the steam flowing through the core space is 75 condensed while the non-condensable gaseous media is cooled. By means of such an arrangement, full utilization is made of the cold 80 end of the tube nest and hence such a type of condenser has a greater heat absorbing capacity consistent with its amount of cooling surface, than condensers of the types heretofore employed. 85

Referring now to the drawings, I show in Figs. 1 to 4, a condenser having a shell structure 10 provided with an inlet 11 for steam to be condensed and an outlet 12 for condensate. Secured to one end of the shell structure 10 is a tube sheet 13 and to the other end a tube sheet 14. Extending longitudinally between the tube sheets 13 and 14 is a tube nest 15, which tube nest has its outer perimeter so formed, as to define, with the interior of the shell structure 10, an intervening steam delivery space 16 surrounding a substantial portion of the tube nest and freely communicating with the inlet 11. 90

Secured to the end tube sheet 13 is an inlet water box 17 having an inlet 17' for supplying cooling water to the tube nest and, secured to the tube sheet 14, is a discharge water box 18 having an outlet 18', the embodiment illustrated being of the single pass type and the water boxes 17 and 18 being so arranged as to circulate the cooling water through the tube nest in a single, longitudinal direction. The tube nest 15 is provided with a longitudinally-extending core space or cavity 19 which is devoid of tubes. This core space is 100 preferably of substantial cross-sectional area in order to provide for free and uninterrupted circulation of gaseous media longitudinally through the tube nest. As pointed out in my aforesaid patent, a core space of this character can be provided without materially increasing the outer dimensions of the tube nest due to the fact that the number of tubes omitted from the core space may be distributed about the periphery of the nest with little increase in the diameter of the latter. 105

For supporting the tube nest intermediate of the end tube sheets 13 and 14, suitable intermediate tube supporting sheet or sheets 110 21 are provided. As shown in Figs. 3 and 4, the outer perimeter of each intermediate tube supporting sheet is similar and adjacent to that of the tube nest in order that the surrounding steam delivery space 16 may com- 115 120 125 130.

5 municate freely and uninterrupted with the entire tube nest. The intermediate tube supporting sheets divide the condenser, longitudinally, into a series of sections, 22, 23, 24 and 25 of progressively increasing temperatures, the section 22 adjacent the inlet water box 17 being a relatively cold section and the section 25 adjacent the outlet water box being a relatively warm section. In order 10 that these intermediate tube supporting sheets may not interfere with the free and longitudinal flow of the gaseous media through the core space 19, they are provided with centrally disposed openings 26, which openings are preferably in alignment with the core 15 space.

As stated heretofore, the gaseous media travels longitudinally through the core space 19 and, in order that the steam therein may 20 be condensed and the air and other non-condensable gases cooled, I provide, in one or more of the colder sections of the tube nest, for example, the sections 22 and 23, cooling compartments 27 and 28. In order to form 25 these compartments, I locate in the core spaces of each of the sections 22 and 23, cup-shaped baffles 29 and 31, which baffles deflect the gaseous media from the core space radially outward into the tube nest sections. The radial limits of these cooling compartments are 30 defined by circular baffles 32 and 33, which baffles extend about a substantial inner, annular portion of the tube nest. In order that gaseous media from the sections 22 and 23 35 may enter their associate cooling compartments, the respective baffles 32 and 33 are provided with substantial, semi-circular openings 33 and 34 in their lower halves. Air and non-condensable gaseous media are finally removed from the condenser by means of a conduit 35 preferably extending through the inlet water box and having its entrant portion 36 disposed in the interior of the baffle 31.

From the foregoing description the operation 45 of my invention will be apparent—steam to be condensed enters the shell structure 10 through the inlet 11 and surrounds the tube nest in the steam delivery space 16. The steam is drawn radially inward in each 50 of the sections from the perimeter of the tube nest toward the core space 19 and, in its passage across the tube nest, a considerable portion of the steam is condensed and falls to the bottom of the shell structure from whence 55 it drains to the hot well or outlet 12. As stated heretofore, the water in the section 22 of the tube nest has a relatively lower temperature than the water in the section 25, hence the heat head prevailing in the section 22 is 60 higher than the heat head prevailing in the section 25. As a result, there is a natural tendency for the gaseous media to flow from the respective sections 23, 24 and 25 toward the coldest section 22.

65 The gaseous media entering the core space

19 from the sections 24 and 25 therefore flows longitudinally toward the baffle 29 and is deflected outwardly against the tubes of the cooling compartment 27 as indicated by the arrows. In addition, non-condensed gaseous media from the section 23 enters the cooling compartment 27 directly by way of the inlet 33. In the cooling compartment 27, the steam component of the gaseous media is condensed and drains through the opening 33 to 75 the bottom of the shell structure. That portion of the gaseous media which is not condensed reenters the core space 19 and is deflected outwardly into the cooling compartment 28 by the baffle 31. The compartment 80 28, being relatively colder than the compartment 27, the non-condensable gaseous media are further cooled and are thence withdrawn through the conduit 35. The condensed steam drains through the opening 34 to the 85 bottom of the shell structure, the opening 34 also serving to allow gaseous media from the section 22 to enter the cooling compartment 28 direct.

From the foregoing, it will be apparent 90 that I have devised a condenser wherein the warmer sections of the tube nest, for example, the sections 24 and 25, are fully utilized and wherein additional gaseous media entering these sections is permitted to flow to the 95 colder sections, that is, the sections 22 and 23. In other words, the natural tendency for the gaseous media to flow to the region of relatively high heat head is not interfered with and hence the coldest sections of the tube 100 nest are fully utilized. As a result, the capacity of the condenser, as a whole, is materially improved. Furthermore, the gaseous media traveling through the tube nest is subjected to the successive cooling actions of the 105 compartments 27 and 28 so that the non-condensable gaseous media leaves the condenser at a temperature closely approaching that of the inlet water box 17.

In the foregoing embodiment, I have shown 110 a condenser of the single pass type, but it is to be understood that my invention is also applicable to condensers of the multi-pass type; and, referring now to Figs. 5 and 6, I show a condenser of the two pass type which is similar to that shown in Figs. 1 to 4 in its essential features. However, in the second embodiment, an inlet water box 41 for supplying cooling water to the tube nest 15 and an outlet water box 42 are both located at the same 115 end of the tube nest. Water is supplied to the tube nest through the inlet water box 41, flows longitudinally through the lower portion of the tube nest and returns through the upper portion of the tube nest via a return water box 43, the water finally leaving the condenser through the outlet water box 42. Preferably, the inlet and outlet water boxes 120 41 and 42 are formed in a single, unitary structure, all as is well known in the art. 130

As stated heretofore, the cooling compartments 27 and 28 are disposed adjacent to the inlet water box, and hence, in the embodiment shown in Figs. 5 and 6, I so arrange the 5 wall 44 which divides the inlet and outlet water boxes that it curves upwardly in alignment with the baffle 33. By means of such an arrangement, water of the first pass travels through the cooling compartments 27 and 10 28 and hence the temperature of the gases removed from the condenser is approximately that of the water supplied to the inlet water box 41.

It will, therefore, be apparent that my invention 15 is applicable to both condensers of the single and multi-pass types, and while, in the foregoing embodiments, I show condensers having their core spaces or cavities entirely surrounded by tubes, it is to be understood that it is within the purview of my invention to so arrange the tube nest that the longitudinally extending core space or cavity is not entirely surrounded by tubes and that it is also within the purview of my invention 20 to form the tube nest with more than one longitudinally extending core space or cavity.

While I have shown my invention in two forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically 35 set forth in the appended claims.

What I claim is:

1. In a condenser, the combination of a shell structure having an inlet for gaseous media to be condensed and an outlet for condensate, a tube nest extending longitudinally through the shell structure, and exposed throughout its length to the gaseous media from the inlet an inlet water box for supplying cooling water to the tube nest, an outlet 40 water box for receiving the cooling water discharged by the tube nest, said tube nest being so formed as to embody a longitudinally-extending cavity having an unrestricted flow-area for affording circulation of gaseous media to a portion of the shell structure adjacent the inlet water box, means communicating with the cavity near the inlet water box for removing noncondensed gaseous media from the shell structure, and means 45 embodied in the tube nest adjacent to the inlet water box for cooling the air and non-condensed gaseous media prior to the removal of the same from the condenser, said last-mentioned means comprising a wall structure embracing a portion of the tube nest adjacent to the cavity and a baffle for deflecting gaseous media outwardly from the cavity into 50 said embraced portion of the tube nest.

2. In a condenser, the combination of a shell structure having an inlet for gaseous

media to be condensed and an outlet for condensate, a tube nest extending longitudinally through the shell structure, and exposed throughout its length to the gaseous media from the inlet an inlet water box for supplying cooling water to the tube nest, an outlet water box for receiving the cooling water discharged by the tube nest, tube sheets, located at each end and intermediate of the ends of the tube nest for supporting the latter, said intermediate tube supporting sheets being provided with openings of unrestricted flow-area and said tube nest being so formed as to embody a longitudinally-extending cavity for affording circulation of gaseous media through the openings in the intermediate tube supporting sheets to a portion of the shell structure adjacent the inlet water box, means communicating with the cavity near the inlet water box for removing non-condensed gaseous media from the shell structure, and means embodied in the tube nest adjacent to the inlet water box for cooling the air and non-condensed gaseous media prior to the removal of the same from the shell structure, said last-mentioned means comprising a wall structure embracing a portion of the tube nest adjacent to the cavity and a baffle for deflecting gaseous media outwardly from the cavity into said embraced portion of the tube nest.

3. In a condenser, the combination of a shell structure having an inlet for gaseous media to be condensed and an outlet for condensate, a hollow nest of tubes disposed within the shell structure and spaced therefrom so that a substantial portion of the outermost tubes of the nest define, with the shell, an arcuate steam delivery space in connection with said inlet, an inlet water box associated with one end of the tube nest and defining a cold end thereof and an outlet water box associated with the other end of the tube nest and defining a relatively warm end thereof, said water boxes providing for the circulation of cooling water in a single, longitudinal direction through the tube nest and said hollow tube nest providing a longitudinally-extending core space for the circulation of gaseous media from the warm toward the cold end of the condenser, means for removing non-condensed gaseous media from the cold end of said core space, and means arranged within the cold end of the tube nest for cooling the non-condensed gaseous media prior to the removal of the same from the condenser, said last-mentioned means comprising a wall structure embracing a portion of the tube nest adjacent to the core space and a baffle for deflecting gaseous media outwardly from the core space into said embraced portion of the tube nest.

4. In a condenser, the combination of a shell structure having an inlet for gaseous media to be condensed and an outlet for con-

densate, a hollow nest of tubes disposed within the shell structure and spaced therefrom so that a substantial portion of the outermost tubes of the nest define, with the shell structure, an arcuate steam delivery space in connection with said inlet, an inlet water box associated with one end of the tube nest and defining a cold end thereof and an outlet water box associated with the other end of the tube nest and defining a relatively warm end thereof, said water boxes providing for the circulation of cooling water in a single, longitudinal direction through the tube nest and said hollow tube nest providing a longitudinally extending core space for the circulation of gaseous media from the warm toward the cold end of the condenser, tube sheet or sheets disposed intermediate of the ends of the tube nest for supporting the latter, said intermediate tube supporting sheets being provided with an opening or openings of substantial flow area disposed in the core space, means for removing non-condensed gaseous media near the cold end of said core space, and means provided in the tube nest near the cold end thereof and adjacent to the core space for cooling the non-condensed gaseous media prior to its removal from the condenser, said last-mentioned means comprising a wall structure embracing a portion of the tube nest adjacent to the core space and a baffle for deflecting gaseous media outwardly from the core space into said embraced portion of the tube nest.

5. In a condenser, the combination of a shell structure having an inlet for gaseous media to be condensed and an outlet for condensate, a hollow nest of tubes disposed within the shell structure and extending longitudinally therethrough, an inlet water box associated with one end of the tube nest and an outlet water box associated with the other end of the tube nest, said water boxes providing for the circulation of cooling water in a single, longitudinal direction through the tube nest, tube sheets located at each end of the tube nest and intermediate of the latter and dividing the tube nest longitudinally, into a plurality of sections having progressively increasing temperatures in a direction from the inlet water box toward the outlet water box, said intermediate tube supporting sheets being provided with openings and said hollow nest of tubes forming a core space communicating with said openings for the longitudinal circulation of gaseous media from the warmer sections of the tube nest to the coldest section, a baffle structure disposed in the coldest section of the tube nest, said baffle structure extending about the core space and a portion of the tube nest adjacent thereto so as to form a cooling chamber, a second baffle structure for directing gaseous media within said cooling chamber, and out-

let means for the removal of gaseous media communicating with the cooling chamber.

6. In a condenser, the combination of a shell structure having an inlet for gaseous media to be condensed and an outlet for condensate, a hollow nest of tubes disposed within the shell structure and extending longitudinally therethrough, an inlet water box associated with one end of the tube nest and an outlet water box associated with the other end of the tube nest, said water boxes providing for the circulation of cooling water in a single, longitudinal direction through the tube nest, tube sheets located at each end of the tube nest and intermediate of the latter and dividing the tube nest longitudinally, into a plurality of sections having progressively increasing temperatures in a direction from the inlet water box toward the outlet water box, said intermediate tube supporting sheets being provided with openings and said hollow nest of tubes forming a core space communicating with said openings for the longitudinal circulation of gaseous media from the warmer sections of the tube nest to the coldest section, baffle structures disposed in a plurality of the coldest sections of the tube nest, each of said baffle structures extending about the core space and the portion of the tube nest adjacent thereto so as to form communicating cooling chambers in each of said sections, additional baffle structures in the core space for directing gaseous media from the core space through the cooling chambers in series, and means for removing the cooled gaseous media from the cooling chamber in the coldest section of the tube nest.

7. In a condenser, the combination of a shell structure having an inlet for steam to be condensed and an outlet for condensate, a tube nest extending longitudinally through the shell structure, an inlet water box for supplying cooling water to the tube nest, an outlet water box for receiving the cooling water discharged by the tube nest, supporting tube sheets located at each end and intermediate of the ends of the tube nest and dividing the latter, longitudinally, into a plurality of sections, said intermediate tube supporting sheets being provided with openings of unrestricted flow-area and said tube nest being so formed as to embody a longitudinally-extending cavity for affording circulation of gaseous media through the openings in the intermediate tube sheets and toward the inlet water box, a cylindrical baffle structure forming a longitudinally-extending cooling chamber in the section of the tube nest adjacent the inlet water box, said cylindrical baffle structure surrounding a portion of the tube nest adjacent to the cavity and said cylindrical baffle structure having an opening in its side remote from the steam inlet for the admission to the cooling chamber of gaseous media from the portion of the tube nest dis-

posed outwardly of the cooling chamber, air removal means communicating with the core space in the section of the tube nest adjacent the inlet water box, and a second baffle structure spaced from the inlet water box, said second baffle structure occupying the core space so as to deflect gaseous media from the core space into the cooling chamber.

5 In testimony whereof, I have hereunto
10 subscribed my name this 3rd day of December, 1929.

JOHN H. SMITH.
